UNITED STATES PATENT OFFICE.

THOMAS FRANCIS SOMERS, OF NEW YORK, N. Y.

DESIGN FOR A DISPLAY-FORM FOR CORSETS.

SPECIFICATION forming part of Design No. 24,250, dated April 23, 1895.

Application filed March 8, 1895. Serial No. 541,046. Term of patent 14 years.

To all whom it may concern:

Be it known that I, THOMAS FRANCIS SOMERS, a citizen of the United States, residing in the city, county, and State of New York, 5 have invented and produced a new and useful Design for a Display-Form for Corsets, of which the following is a specification.

My new and original design relates to display forms for corsets, and it has for its object to provide a display form having an attractive and aesthetic shape or configuration that will appeal to the eyes of the public, and to these ends my invention consists in a design embodying the essential features substantially as hereinafter more particularly set forth.

In the accompanying drawings: Figure 1 is a front view of a display form embodying my invention; and Fig. 2 is a vertical transverse 20 section of the same.

The leading features of my design consist of a central form representing a headless and armless trunk or body circumscribed by a band. Thus, in the accompanying drawings,

A, represents the trunk or body, representing 25 the shoulders a , bust a' , back a'' , neck a''' , waist a''' , and hips a'''' , of the human form or body, the lines being curved to form a body of ideal shape or configuration. This trunk A, is circumscribed by a band B, which is 30 shown in the form of an annular band, a portion of the inner edges of the band contacting with the lower extremities of the body portion A.

My invention is a design including as its 35 essential feature a central form representing a headless and armless trunk or body circumscribed by a band.

What I claim is—

The design substantially as above described 40 and shown.

In testimony whereof I have signed my name to this specification in the presence of two subscribing witnesses.

THOMAS FRANCIS SOMERS.
